UNITED STATES PATENT OFFICE

HENRY WOLF, OF BROOKLYN, NEW YORK

PUMP CONSTRUCTION

Application filed February 20, 1931. Serial No. 517,280.

This invention relates to footwear, and particularly to an improved shoe commonly known as a pump, the object being to provide a simple, comfortable construction and a pleasing appearance and one that will not pinch the foot near the front thereof.

Another object is to provide an improved pump wherein a tongue integral with the upper is provided and bent to extend toward the toe beneath the lining.

A further object, more specifically, is to provide a tongue for a pump made of an appreciable width and length so that it may be readily connected with the trimming and the lining of the pump in such a way as to present a comparatively large smooth surface whereby pinching the foot at this point is prevented.

In the accompanying drawing—

20 Figure 1 is a plan view of a blank upper showing a tongue constructed according to the present invention.

Figure 2 is an enlarged fragmentary interior view of the tongue shown in Figure 1, 25 and associated parts, when in condition for use.

Figure 3 is a sectional view through Figure 2 on line 3—3.

Figure 4 is a perspective view of the complete pump on a reduced scale, the same illustrating the line of bending of the tongue.

Referring to the accompanying drawing by numeral, 1 indicates an ordinary heel and 2 the usual sole for pumps. Connected in the usual manner with these members is an upper 3 which is of the usual construction except for the tongue 4 and associated parts as illustrated in Figures 1 to 3 inclusive. From the upper blank shown in Figure 1, 40 it will be noted that the tongue 4 is integral with the upper and made of an appreciable length and width so that when it is bent underneath and stitched in place, it will present a broad smooth surface which will not pinch or cut the foot.

The pump is provided with what may be termed inner and outer linings 5 and 6 as well as the trimming lining 7. The linings 5 and 6 are preferably canvas, while the trimming lining is preferably leather and stitched

in place in a desirable manner by suitable lines of stitching 8 and 9. At the front or directly beneath the tongue 4, as shown in Figure 2, the ornamental lining 7 falls short or does not meet. This prevents an undesirable thickness at this point. However, the line of stitching 10 furnishes means to hold the tongue 4 in proper place and connects the same along two sides and one end with the ornamental lining 7 and the canvas lining 5. A strip 11 is also provided which acts as a padding and filler member at this point, said member extending only a short distance on each side of the tongue. By reason of this construction, there is provided a smooth bend or edge 12 for tongue 4 which is without stitching along this edge and which is comfortable and will not pinch or cut the foot when the pump is in use. The stitching 10 furthermore holds the ornamental lining 7 and the canvas lining 5 in position between the tongue and the upper 3, without the necessity of other stitching in the region of the fold 12.

As illustrated in Figure 4, the pump is of the usual appearance of pumps and consequently does not have a strap or other means for holding the same in place. The upper fits naturally against the rear of the heel of the person wearing the pump and also over the upper part of the foot, including the part of the foot immediately in front of the instep. It will therefore be seen that the pump is really held in place on the foot by the parts at line 12 coacting with the heel part 80 of the upper. This strain would produce a pressure or cutting action on the foot except for the fact that the tongue 4 presents a smooth bend or edge 12 that is soft and distributes the strain and consequently produces 85 a very comfortable structure.

I claim—

1. A pump including an upper formed with an integral tongue at the front of the opening thereof, said tongue being bent beneath the upper and positioned to extend toward the toe portion whereby a smooth edge is presented in the front opening of the upper and a comparatively wide smooth surface adjacent thereto, a lining for said upper, and

stitching along the side edges of said tongue connecting the tongue to the lining and holding the tongue in position, said stitching being entirely beneath the upper whereby it

5 cannot be seen when the pump is worn.

2. An article of footwear including an upper and suitable lining therefor, said upper being provided with an integral tongue bent to underlie the lining and to extend an appreciable distance toward the toe portion and a line of stitching along the side edges and across the forward end of said tongue connecting the tongue to the lining and holding the tongue in position, said stitching being

15 entirely beneath the upper whereby it cannot be seen when the footwear is worn.

Signed at 521 5th Ave. in the county of New York and State of New York this 19 day of February 1931.
